GAME BOARD INDICATOR

Joseph A. Slais, 425 Shenstone Road, Riverside, Ill.

Filed July 21, 1960, Ser. No. 61,467

Term of patent 14 years

(Cl. D34—5)

Fig. 1.

Fig. 2.

The dominant features of the design reside in the portions shown in full lines.

I claim:

The ornamental design for a game board indicator, substantially as shown and described.
